DESIGN FOR A COMBINED MASCARA APPLICATOR AND EYELASH CURLER

Arthur O. Hanisch, Altadena, Calif.

Application January 23, 1941, Serial No. 98,300

Term of patent 14 years

To all whom it may concern:

Be it known that I, Arthur O. Hanisch, a citizen of the United States, residing at Altadena, County of Los Angeles, and State of California, have invented a new, original, and ornamental design for a Combined Mascara Applicator and eyelash Curler, of which the following is a specification, reference being had to the accompanying drawing, forming part thereof.

The dominant features of the design reside in the portions shown in full lines.

I claim:

The ornamental design for a combined mascara applicator and eyelash curler, as shown and described.

ARTHUR O. HANISCH.
